HYDRAULIC ELEVATOR

De Witt E. Yates, Chippewa Falls, Wis., assignor
to W. S. Darley & Company, Chicago, Ill., a corporation of Illinois

Application November 20, 1951, Serial No. 257,389

1 Claim. (Cl. 189—14)

1

The present invention relates generally to hydraulic elevators. More particularly the invention relates to that type of elevator which is designed primarily to elevate and lower a load and comprises a normally vertical series of telescopedically connected tubes which, when supplied internally with fluid under pressure, slide apart into an extended position and, when the fluid is released, slide together into a collapsed or nested position.

One object of the invention is to provide an hydraulic elevator which is an improvement upon, and has certain inherent advantages over, previously designed elevators of the same general type and is characterized by high efficiency, simplicity of design and low cost of manufacture.

Another object of the invention is to provide an hydraulic elevator of the type under consideration in which the tubes are provided with simple and novel means whereby they are effectively and efficiently stabilized against lateral deflection or bending when in their extended position as the result of the supply of fluid under pressure to their interiors.

Another object of the invention is to provide an hydraulic elevator of the last mentioned character in which the stabilizing means for the telescopedically connected tubes comprises spiders which are fixedly connected to the upper ends of the tubes and consist of hubs and radially extending arms, and also comprises rigid rod-type truss elements which extend between, and are operatively connected to, the arms of the spiders and are so arranged and designed that they are placed under tension when the tubes are slid apart into their extended position.

Another object of the invention is to provide an hydraulic elevator of the aforementioned type in which the truss elements are in the form of V-shaped rods which are so arranged and designed that they nest when the tubes are slid together into their collapsed position.

A further object of the invention is to provide an hydraulic elevator which is generally of new and improved construction, has numerous capabilities of use, effectively and efficiently fulfills its intended purpose and is compact when not in use.

Other objects of the invention and the various advantages and characteristics of the present hydraulic elevator will be apparent from a consideration of the following detailed description.

The invention consists in the several novel features which are hereinafter set forth and are more particularly defined by the claim at the conclusion hereof.

2

In the drawings which accompany and form a part of this specification or disclosure and in which like numerals of reference denote corresponding parts throughout the several views:

5 Figure 1 is a vertical section showing an hydraulic elevator embodying the invention in its extended position;

Figure 2 is a horizontal section taken on the line 2—2 of Figure 1 and illustrating the construction and design of one of the spiders;

10 Figure 3 is an enlarged vertical section taken on the line 3—3 of Figure 1 and showing in detail the construction of the stuffing boxes at the upper ends of all of the tubes with the exception of the uppermost tube;

15 Figure 4 is a vertical section showing the elevator in partially elevated position and illustrating the manner in which the pull-down cable serves as a positive stop for limiting extension of the tubes to a particular elevation;

Figure 5 is a vertical section illustrating the elevator in its collapsed position; and

20 Figure 6 is a fragmentary view, partly in section and partly in elevation, showing the construction and arrangement of the V-shaped truss rods and illustrating the manner in which they are operatively connected to the arms of the spiders at the upper ends of the tubes.

25 The hydraulic elevator which is shown in the drawings constitutes the preferred form or embodiment of the invention. It is designed primarily to elevate and lower a load and comprises a plurality of telescopedically connected tubes. Four tubes are shown in the drawings and these are designated by the reference numerals 7, 8, 9 and 10. Whereas four tubes are shown it is to be understood that more or less tubes may be employed, depending upon whether it is desired to increase or decrease the over-all height of the elevator when the latter is in its extended position.

30 The tubes are shown as extending vertically. It is contemplated, however, that in some instances the elevator may be tilted or tipped from a position wherein the tubes extend truly vertically. The tubes 7, 8, 9 and 10 are circular in cross section, as shown in Figure 2, and are formed of steel, stainless steel, aluminum or any other suitable strong rigid material.

35 The tube 7 is what may be termed the lowermost tube and has its lower end closed by a cross-wall 11. It is provided at its lower end with a base 12 and embodies at its upper end a stuffing box 13 and a spider 14. The base 12 is rigidly connected to the lower end of the tube 7 and is of such size that it serves, when resting on a flat 40 surface, to hold the elevator, in connection with

extension thereof, in a stable manner. The stuffing box 13 at the upper end of the tube 7 consists of an annulus 15 of packing material and an inverted cup-shaped nut 16. The nut embodies a centrally apertured top wall and a side wall which is connected to, and depends from, the outer marginal portion of the top wall, surrounds the upper end of the tube 7 and is connected to such tube by a screw thread connection. The annulus 15 fits within the depending side wall of the nut 16 and is interposed between the upper end of the tube 7 and the superjacent portion of the cross-wall of the nut. The spider 14 consists of an annular hub 17 and a plurality of radially extending arms 18. The hub 17 of the spider 14 extends around, and is welded or otherwise fixedly secured to, the upper end of the tube 7 and is disposed a small distance beneath the stuffing box 13. The arms 18 are preferably four in number and are connected to, and project outwards from, the hub 17. They are spaced equidistantly apart and embody laterally extending lugs 19 at points directly inwards of their outer extremities. These lugs are preferably formed as integral parts of the arms 18 and have vertically extending holes therein. The arms 18 of the spider 14 are supported by way of vertically extending standards 20, the lower ends of which are connected to the base 12 by triangular gusset plates 21 and the upper ends of which are connected to the outer ends of the arms 18 by triangular gusset plates 22.

The tube 8 is open ended and embodies at its upper end a stuffing box 23 and a spider 24. It is of uniform diameter from end to end and extends slidably through the stuffing box 13 at the upper end of the tube 7 so that it is capable of sliding upwards and downwards relatively to the tube 7. The external diameter of the tube 8 is substantially the same as the internal diameter of the tube 7 in order that the sliding connection between the tube 8 and the tube 7 is comparatively tight. The stuffing box 23 at the upper end of the tube 8 is the same in design and construction as the stuffing box 13 at the upper end of the tube 7 and consists of an annulus 25 of packing material and an inverted cup-shaped nut 26. The nut 26 comprises a centrally apertured end wall and a cylindrical side wall which is connected to, and depends from, the outer marginal portion of the end wall, surrounds the upper end of the tube 8 and is connected thereto by a screw thread connection 27 (see Fig. 3). The annulus 25 of the stuffing box 23 fits within the side wall of the nut 26 and is interposed between the upper end of the tube 8 and the superjacent portion of the end wall of said nut 26. The spider 24 consists of an annular hub 28 and four radially extending arms 29. The hub 28 extends around, and is welded or otherwise fixedly secured to, the upper end of the tube 8 and is disposed a small distance beneath the stuffing box 23. The arms 29 are connected to, and project outwards from, the annular hub 28 and directly overlie, but are of less length than, the arms 18 of the spider 14. The outer ends of the arms 29 are provided with laterally extending lugs 30 and these are vertically aligned with the laterally extending lugs 19 on the arms 18 of the spider 14 and have vertically extending holes therethrough. The inner ends of the arms 29 are provided with laterally extending lugs 31 and these are preferably formed as integral parts of the arms 29 and have vertical holes therethrough. The spider arms 29 have in addition to the lugs 30 and 31 integral laterally extending lugs 32 and these are disposed a small

distance inwards of the lugs 30 and have vertical holes therethrough. Associated respectively with, and depending from, the four arms 29 of the spider 24 are four V-shaped truss rods 33. The purpose of these truss rods is to limit upward sliding movement of the tube 8 with respect to the tube 7 and also to prevent lateral deflection or bending of the tube 8 when it is in its extended position. The truss rods 33 comprise outer parts 34 and inner parts 35. The outer parts 34 are vertically disposed and extend slidably through the holes in the lugs 19 on the outer ends of the arms 18 of the spider 14. The upper ends of the outer parts 34 extend through the holes in the lugs 30 and are provided with pairs of vertically spaced nuts 36 which straddle the lugs 30 and serve fixedly to connect the upper ends of the outer parts 34 to said lugs. The inner parts 35 of the truss rods 33 have the lower ends connected to the lower ends of the outer parts 34 by U-shaped connecting parts 37 and extend upwards and inwards at a comparatively small acute angle with respect to the outer parts 34. The upper ends of the inner parts 35 extend through the holes in the lugs 31 and are provided with pairs of spaced apart nuts 38 which are in straddled relation with the lugs 31 and serve fixedly to connect the upper ends of the inner parts 35 of said lugs. When the tube 8 is slid upwards and downwards with respect to the tube 7 the outer parts 34 of the V-shaped truss rods 33 slide through the lugs 19 on the outer ends of the arms 18 of the spider 14. The U-shaped connecting parts 37 between the lower ends of the outer parts 34 and the inner parts 35 coat with the lugs 19 to limit upward sliding movement of the tube 8 with respect to the tube 7. The tube 8 is caused to slide upwards with respect to the tube 7 when fluid under pressure is introduced into the tubes 7 and 8. When the tube 8 is slid upwards to its fullest extent the pressure of the fluid places the truss rods under tension and causes them to stabilize the tube 8 against lateral deflection or bending relatively to the tube 7. When the tube 8 is slid downwards with respect to the tube 7 the truss rods 33 are disposed inwards of the standards 20, as shown in Figure 5.

The tube 9 is open ended and embodies at its upper end a stuffing box 39 and a spider 40. It is of uniform diameter from end to end and extends slidably through the stuffing box 23 at the upper end of the tube 8. The external diameter of the tube 9 is substantially the same as the internal diameter of the tube 8 in order that the sliding connection between the tube 9 and the tube 8 is comparatively tight. The stuffing box 39 at the upper end of the tube 9 is the same in design and construction as the stuffing boxes 13 and 23 at the upper ends of the tubes 7 and 8 and consists of an annulus 41 of packing material and an inverted cup-shaped nut 42. The nut 42 comprises a centrally apertured end wall and a cylindrical side wall which is connected to, and depends from, the outer marginal portion of the end wall, surrounds the upper end of the tube 9 and is connected thereto by a screw thread connection. The annulus 41 of the stuffing box 39 fits within the side wall of the nut 42 and is interposed between the upper end of the tube 9 and the superjacent portion of the end wall of said nut 42. The spider 40 consists of an annular hub 43 and four radially extending arms 44. The hub 43 extends around, and is welded or otherwise fixedly secured to, the upper end of the tube 9 and is disposed a small distance inwards of the lugs 30 and 31 integral laterally extending lugs 32 and these are disposed a small

beneath the stuffing box 39. The arms 44 are connected to, and project outwards from, the annular hub 43 and directly overlie, but are of less length than, the arms 29 of the spider 24. The outer ends of the arms 44 are provided with integral laterally extending lugs 45 and these are vertically aligned with the laterally extending lugs 32 on the arms 29 of the spider 24 and have vertically extending holes therethrough. The inner ends of the arms 44 are provided with laterally extending lugs 46 and these are preferably formed as integral parts of the arms 44 and have vertical holes therethrough. The spider arms 44 have in addition to the lugs 45 and 46 integral laterally extending lugs 47 and these are disposed a small distance inwards of the lugs 45 and have vertical holes therethrough. Associated respectively with, and depending from, the four arms 44 of the spider 40 are four V-shaped truss rods 48. The purpose of these truss rods is to limit upward sliding movement of the tube 9 with respect to the tube 8 and also to prevent lateral deflection or bending of the tube 9 when it is in its extended position. The truss rods 48 comprise outer parts 49 and inner parts 50. The outer parts 49 are vertically disposed and extend slidably through holes in the lugs 32 on the outer ends of the arms 29 of the spider 24. The upper ends of the outer parts 49 extend through the holes in the lugs 32 and are provided with pairs of vertically spaced nuts 51 which straddle the lugs 45 and serve fixedly to connect the upper ends of the outer parts 49 to said lugs. The inner parts 50 of the truss rods 48 have their lower ends connected to the lower ends of the outer parts 49 by U-shaped connecting parts 52 and extend upwards and inwards at an acute angle which is slightly smaller than the angle between the outer and inner parts 34 and 35 of the truss rods 33. The upper ends of the inner parts 50 extend through the holes in the lugs 46 and are provided with pairs of vertically spaced apart nuts 53 which are in straddled relation with the lugs 46 and serve fixedly to connect the upper ends of the inner parts 50 to said lugs. When the tube 9 is slid upwards and downwards with respect to the tube 8 the outer parts 49 of the V-shaped truss rods 48 slide through the lugs 32 on the outer ends of the arms 29 of the spider 24. The U-shaped connecting parts 52 between the lower ends of the outer parts 49 and the inner parts 50 coact with the lugs 32 to limit upward sliding movement of the tube 9 with respect to the tube 8. The tube 9 is caused to slide upwards with respect to the tube 8 when fluid under pressure is introduced into the tube assembly. When the tube 9 is slid upwards to its fullest extent the pressure of the fluid places the truss rods 48 under tension and causes them to stabilize the tube 9 against lateral deflection or bending relatively to the tube 8. The tube 9 and the truss rods 48 are, respectively, shorter than the tube 8 and the truss rods 33, and the truss rods 48 are so arranged and shaped that when the tube 9 is lowered with respect to the tube 8 they fit or nest in the truss rods 33, as shown in Figure 5.

The tube 10 is open at its lower end and closed at its upper end and embodies a spider 54. It is of uniform diameter from end to end and extends slidably through the stuffing box 39 at the upper end of the tube 9 so that it is capable of sliding upwards and downwards relatively to the tube 9. The external diameter of the tube 10 is substantially the same as the internal diameter of the tube 9 in order that the sliding connection

between the tube 10 and the tube 9 is comparatively tight. The spider 54 consists of an annular hub 55 and four radially extending arms 56. The hub 55 extends around the upper end of the tube 10 and is welded or otherwise fixedly secured thereto. The arms 56 are connected to, and project outwards from, the hub 55 and directly overlie, but are of less length than, the arms 44 of the spider 40. The outer ends of the arms 56 are provided with integral laterally extending lugs 57 and these are vertically aligned with the laterally extending lugs 47 on the arms 44 of the spider 40 and have vertically extending holes therethrough. The inner ends of the arms 56 are provided with laterally extending lugs 58 and these are preferably formed as integral parts of the arms 56 and have vertical holes therethrough. Associated respectively with, and depending from, the four arms 56 of the spider 54 are four V-shaped truss rods 59. The purpose of these truss rods is to limit upward sliding movement of the tube 10 with respect to the tube 9 and also to prevent lateral deflection or bending of the tube 10 when it is in its extended position. The truss rods 59 comprise outer parts 60 and inner parts 61. The outer parts 60 are vertically disposed and extend slidably through holes in the lugs 47 on the outer ends of the arms 44 of the spider 40. The upper ends of the outer parts 60 extend through the holes in the lugs 57 and are provided with pairs of vertically spaced nuts 62 which straddle the lugs 57 and serve fixedly to connect the upper ends of the outer part 60 to said lugs. The inner parts 61 of the truss rods 59 are connected to the lower ends of the outer parts 60 by U-shaped connecting parts 63 and extend upwards and inwards at an acute angle which is slightly smaller than the angle between the outer and inner parts 49 and 50 of the truss rods 48. The upper ends of the inner parts 61 extend through the holes in the lugs 58 and are provided with pairs of vertically spaced apart nuts 64 which are in straddled relation with the lugs 58 and serve fixedly to connect the upper ends of the inner parts 61 to said lugs. When the tube 10 is slid upwards and downwards with respect to the tube 9 the outer parts 60 of the V-shaped truss rods 59 slide through the lugs 47 on the outer ends of the arms 44 of the spider 40. The U-shaped connecting parts 64 between the lower ends of the outer parts 60 and the inner parts 61 coact with the lugs 58 to limit upward sliding movement of the tube 10 with respect to the tube 9. The tube 10 is caused to slide upwards with respect to the tube 9 when fluid under pressure is introduced into the tube assembly. When the tube 10 is slid upwards to its fullest extent the pressure of the fluid places the truss rods 59 under tension and causes them to stabilize the tube 10 against lateral deflection or bending relatively to the tube 9. The tube 10 and the truss rods 59 are, respectively, shorter than the tube 9 and the truss rods 48, and the truss rods 59 are so arranged and shaped that when the tube 10 is lowered with respect to the tube 9 they fit and nest in the truss rods 48, as shown in Figure 5 of the drawings. The spider 54 is surmounted by a load supporting platform 65. The latter is suitably secured to arms 56 of the spider 54 so that it is movable up and down with said spider.

When fluid under pressure is introduced into the lowermost tube 7 the tube 8 first slides upwards to its fullest extent, then the tube 9 slides

upwards to its fullest extent and then the tube 10 slides upwards to its fullest extent. When the fluid under pressure within the tube assembly is released the tube 10 first slides down into the tube 9, the tube 9 then slides down into the tube 8 and finally the tube 8 slides downwards into the tube 7. The largest slidable tube, i. e., tube 8, always slides upwards first and retracts last because it has a greater cross sectional area than the tube next above it. The hydraulic pressure that is required to slide upwards each slidable tube is greater the smaller the tube and hence there is a progressive increase in the pressure of the fluid within the tube assembly as the elevator as a whole slides upwards into its extended position. As a result of the progressive increase in the pressure of the fluid within the tube assembly as the elevator rises the tension on the various truss rods increases and, therefore, the stability is greater as the elevator rises as the load increases. Associated with the telescopically connected tubes 7, 8, 9 and 10 is means for supplying the lowermost tube 7 with fluid under pressure in order to effect sliding apart of the tubes into their extended position. Such means comprises a tank 66 and a pump 67. The tank 66 is located at one side of the base 12 and contains a column 68 of liquid, such as oil. The pump 67 is located between the tank 66 and the tube 7 and comprises a casing 69 and a rotor (not shown) within the casing. The casing of the pump embodies an inlet 70 and an outlet 71. The rotor is driven by an electric motor (not shown). The inlet 70 of the pump casing 69 is connected to the lower end of the tank 66 by a pipe 72. The outlet 71 of the pump casing is connected to the lower end of the tube 7 by a pipe 73. When the pump is driven liquid is drawn from the tank 66 through the pipe 72 and is forced under pressure through the pipe 73 into the tube assembly. As heretofore pointed out, supply of fluid under pressure into the tube assembly serves to slide apart the slidable tubes into their extended position. The pipe 73 embodies a globe valve 74 and a check valve 75. The globe valve 74 is located in close proximity to the outlet 71 of the pump casing and serves as a medium for regulating the flow of liquid from the pump to the tube assembly. The check valve 75 is located in the pipe 73 between the globe valve 74 and the tube 7 and serves to prevent reverse flow of liquid through the pump when the pump is not in operation. A by-pass pipe 76 is connected to the pipe 73 at a point between the globe valve 74 and the outlet 71 of the pump casing and leads into the central portion of the tank 66. It serves to by-pass back to the tank the pumpage that occurs when the elevator is extended to its fullest extent while the pump is still in operation. A globe valve 77 is included in the by-pass pipe 76 and serves to control the flow of excess pumpage through such pipe. A return pipe 78 has one end thereof connected to the pipe 73 at a point between the check valve 75 and the tube 7. The other end of the return pipe is connected to the upper end of the tank 66. A globe valve 79 is included in the return pipe 78. When the pump 67 is operated to pump liquid under pressure into the tube assembly the globe valve 79 is closed. When it is desired to lower the elevator the pump 67 is stopped and the globe valve 79 is opened. As soon as such valve is opened the hydraulic pressure within the tube assembly is released and the slidable tubes 10, 9, and 8 slide downwards and the tube 10, the

5 tube 9 and the tube 8 slide downwards in the order mentioned.

10 In addition to the parts heretofore mentioned the elevator comprises a winch 80 and a pull-down cable 81. The winch is mounted on the base 12 in close proximity to the lower end of the tube 7 and embodies a U-shaped mounting bracket 82, and a drum 83 between the upper ends of the side parts of the mounting bracket. The drum 83 is fixed to a shaft 84, the ends of which extend through, and are journalled in, holes in the upper ends of the side parts of the mounting bracket 82. A crank 85 is connected to one end of the shaft and serves as an instrumentality for turning the drum 83. One end of the cable 81 is connected to one of the arms 56 of the spider 54 at the upper end of the tube 10 and the other end of the cable is anchored to, and wound around, the drum 83 of the winch 80. When the globe valve 79 in the return pipe 78 is opened when it is desired to collapse the elevator the cable 81 by proper turning of the crank 85 may be pulled downwards so as to assure downward sliding of the tubes 10, 9 and 8. The pull-down cable 81 is brought into play in the event that binding of the aforementioned tubes occurs. In order to limit paying-out of the cable so as to control as desired the elevation to which the elevator is raised in connection with supply of liquid under pressure to the tube 7 a ratchet wheel 86 and a pawl 87 are provided. The ratchet wheel 86 is fixedly secured to one end of the drum supporting shaft 84. The pawl 87 is disposed adjacent the ratchet wheel and is pivotally connected to one of the side parts of the mounting bracket 82 so that it is capable of being swung into and out of engagement with the teeth of the ratchet wheel. The teeth of the ratchet wheel are arranged so that if the pawl is in engagement therewith the pawl slides over the teeth when the drum is turned by the crank 85 so as to wind the pull-down cable 81 around the drum. It is contemplated that in connection with raising of the elevator the pawl will be swung out of engagement with the teeth of the ratchet wheel. When the elevator has been raised to the desired extent it is contemplated that the operator will swing the pawl into engagement with one of the teeth of the ratchet wheel so as to form a positive stop whereby further raising of the elevator is prevented.

15 The herein described hydraulic elevator has numerous capabilities of use. It may be used in connection with rescue operations at elevations that are out of reach of existing facilities. It may be used to elevate materials to high places in connection with construction operations. It also may be used in connection with cleaning and painting high structures, as well as a medium for supporting the nozzle of a fire hose. Due to its particular design and construction the elevator may be produced at a comparatively low cost and when in its collapsed position occupies but a small space.

20 25 30 35 40 45 50 55 60 65 The invention is not to be understood as restricted to the details set forth since these may be modified within the scope of the appended claim without departing from the spirit and scope of the invention.

Having thus described the invention what I claim as new and desire to secure by Letters Patent is:

70 75 80 85 90 An hydraulic elevator comprising a normally vertical series of concentrically arranged and telescopically connected tubes, the tube of largest diameter having its lower end closed and being

provided with means for supporting it in an up-standing position, the tube of smallest diameter having its upper end closed and provided with load supporting means, said tubes being adapted when supplied internally with liquid under pressure to slide apart into an extended position and when the liquid is released to slide together into a collapsed position, means for supplying liquid under pressure to the interiors of the tubes and releasing it therefrom, spiders connected fixedly to the upper ends of the tubes and provided with rigid outwardly and radially extending substantially vertically aligned arms, the arms of all of the spiders with the exception of the spider on the upper end of the tube of largest diameter being provided with rigid anchoring means and the arms of all of the spiders with the exception of the spider on the upper end of the tube of smallest diameter being provided with members having vertical holes therein, and rigid upstanding rod-type V-shaped truss elements extending between the arms of the spiders, consisting of vertical outer parts, upwardly and inwardly inclined inner parts and integral U-shaped connecting parts between the lower ends of the outer and inner parts, and having the upper end of said outer and inner parts connected fixedly to the anchoring means

5

15

of the superjacent spider arms, said truss elements having the outer parts thereof extending slidably through the holes in the members of the subjacent spider arms, having their U-shaped connecting parts disposed beneath said members, and being of slightly less length than the tubes and so constructed and designed that when the tubes are slid apart to substantially their fullest extent said U-shaped connecting parts abut against said members and result in the truss elements serving to limit further sliding apart of the tubes and being placed under such tension that they operate through the medium of the spiders to stabilize the tubes against lateral deflection or bending, said truss elements being so proportioned and positioned that they nest when the tubes are in their collapsed position.
